(57) **CLAIM**

The ornamental design for a post and cassette housing for queue management system, as shown and described.

DESCRIPTION

FIG. 1 is a front perspective view of a post and cassette housing for queue management system;

FIG. 2 is an enlarged rear perspective view of the housing and stem portion;

FIG. 3 is an enlarged front perspective view of the housing and stem portion;

FIG. 4 is an enlarged right side perspective view of the housing and stem portion;

FIG. 5 is an enlarged left side perspective view of the housing and stem portion;

FIG. 6 is a top plan view thereof;

FIG. 7 is a bottom plan view thereof;

FIG. 8 is an enlarged rear perspective view of the housing portion;

FIG. 9 is an enlarged front perspective view of the housing portion;

FIG. 10 is an enlarged right side perspective view of the housing portion;

FIG. 11 is an enlarged left side perspective view of the housing portion;

FIG. 12 is an enlarged top plan view thereof;

FIG. 13 is a front perspective view of a second embodiment of a post and cassette housing for queue management system;

FIG. 14 is an enlarged rear perspective view of the central housing portion;

FIG. 15 is an enlarged front perspective view of the central housing portion;

FIG. 16 is an enlarged right side perspective view of central housing portion;

FIG. 17 is an enlarged left side perspective view of the central housing portion; and,

FIG. 18 is a cross sectional view taken along line 18—18 of FIG. 14.
